UNITED STATES PATENT OFFICE.

VINCENT E. HEYWOOD, OF WORCESTER, MASSACHUSETTS.

WINDOW-ENVELOP.

1,304,877.

Specification of Letters Patent. Patented May 27, 1919.

Application filed December 21, 1916. Serial No. 138,190.

To all whom it may concern:

Be it known that I, VINCENT E. HEYWOOD, a citizen of the United States, residing at Worcester, in the county of Worcester and State of Massachusetts, have invented certain new and useful Improvements in Window-Envelops, of which the following is a specification.

My invention relates to a window, or open face envelop, so-termed, and to that class of window envelops which are made of opaque material and have an opening therein, through which the inscription on the inclosure will be visible, said opening having no transparent patch to cover said opening.

The object of my invention is to improve upon the construction of envelops of the class referred to, as ordinarily made, and more particularly to make the envelop blank of such a shape that the customary operations of cutting the envelop blank and forming the window opening, may be simultaneous.

My invention consists in certain novel features of construction of my envelop, as will be hereinafter described.

In the ordinary construction of a window envelop of the class referred to, the window or opening is made through the body of the envelop blank and within the edges of the blank. In my improved construction the window or opening is not made through the body of the blank, but is made by recessing, or cutting out, the edge of the top front flap, and the edge of the bottom front flap, so that when the envelop blank is folded the window opening therein will be between the horizontal edges of the top flap, and the bottom flap, as will be hereinafter described.

Referring to the drawing:—

Figure 1 shows my envelop blank, before it is folded; the broken lines indicate the fold lines, and the diagonal lines the gummed surface.

Fig. 2 shows the envelop blank folded, and ready to receive the inclosure.

Fig. 3 shows the envelop with the inclosure therein, and with the seal flap folded down and secured to the envelop proper, and

Fig. 4 shows a modified construction of the envelop shown in Figs. 2 and 3; the broken lines show a side flap before it is folded.

In the accompanying drawing, 1 is the envelop blank, preferably made of opaque

paper, or other material. The blank 1 has the two side flaps 2, and 3, which are of slight width. 4 is the top flap, which is recessed or cut out on its horizontal edge, as shown at 4', leaving the two side extensions 4''.

The two side edges of the top flap 4 preferably have a gummed surface, as shown by cross lines 4'', Fig. 1.

5 is the bottom flap, which is recessed or cut out on its horizontal edge, as shown at 5'. The recess 5' corresponds in conformation to the recess 4' in the flap 4 above described, and has the two extensions 5''. The flap 5 has a gummed surface on the projections 5'', and preferably on that part of the flap intermediate the two extensions 5'', as shown by cross lines 5''', Figs. 1 and 2.

The broken lines 1', Fig. 1, indicate the fold lines, on which lines the side flaps 2, and 3, and the top flap 4, and the bottom or seal flap 5, are folded inwardly or toward each other, to form the finished envelop.

In folding the envelop blank shown in Fig. 1, the side flaps or edges 2, and 3, are first preferably folded inwardly, as indicated by full and broken lines in Fig. 2. The top flap 4 is then folded inwardly and the gummed surface 4''' thereon, pressed down on the side flaps 2, and 3, to secure the top flap 4 thereto as shown in Fig. 2.

The envelop, as shown in Fig. 2, is ready to receive the inclosure, which is inserted in such a manner that the inscription thereon will show through the recessed or cut out portion in the top flap 4. After the inclosure is inserted, the bottom or seal flap 5 is folded in, on the line 1', Fig. 2, and the gummed surface 5''' thereon adheres to the side flaps 2 and 3, and also preferably adheres to the inclosure within the envelop, intermediate the two extensions 5''.

The recessed or cut out portion 5' on the bottom or seal flap 5, in connection with the recessed portion 4' on the top flap 4, when the bottom or seal flap 5 is folded, as shown in Fig. 3, forms the window in the envelop, to show the inscription on the inclosure therein, as shown in Fig. 3.

In Fig. 4, the envelop is open at one end, by means of one of the side or edge flaps, as 3, which is provided with a gummed surface, not shown, on its top side, and is not folded in until after the other side flap, and the bottom, and the top flaps, are folded in

and secured together by the gummed surface. The inclosure is inserted through the open end, and after it is inserted, the end flap, as 3, is folded in, and secured by the 5 gummed surface thereon, to the bottom, and the top flaps, to form the completed envelop, as shown in Fig. 4.

The advantages of my improved window envelop will be readily appreciated by those 10 skilled in the art.

It will be understood that the details of construction of my improved window envelop may be varied if desired.

The shape of the recess, or cut out portion, 15 in the top flap, and in the bottom flap, may be varied if desired, so that the opening formed in the envelop may have square ends, instead of round, if preferred, and the width of the opening may be varied as desired.

20 The gummed surface on the side flaps, and on the top flap, and on the bottom flap, may

be varied or changed if desired. The shape of the side flaps may be varied if desired.

Having thus described my invention, what I claim as new and desire to secure by Let- 25 ters Patent is:

As an improved article of manufacture, a window envelop, comprising a body having two side flaps, and a top flap, and a bottom flap, the top flap and the bottom flap re- 30cessed or cut out on their edges to provide a window or opening, and having projec- 35tions thereon extending beyond the recessed portions, which projections are adapted to butt against each other, and form the ends of the window or opening, and said top and bottom flaps extending over the side flaps, and gummed thereto.

VINCENT E. HEYWOOD.
